UNITED STATES PATENT OFFICE.

AUGUST G. SANDMAN, OF BALTIMORE, MARYLAND.

CORNER POST FOR DROP-END GONDOLA CARS.

Application filed July 30, 1925. Serial No. 47,032.

This invention relates to corner post for that type of railway freight train equipment known as the drop end gondola car. Such a car is provided with rigid side walls but the end walls are hinged at their bottom edge so that they may be lowered or dropped so as to lie on the floor of the car. The object of such an arrangement is to permit the car to be used in transporting material which is too long to be carried in one car, such as rolled steel beams, pipe and fabricated structural material. When the doors are in an upright or closed position, the car is used as an ordinary gondola car. The corner post of such a car performs several functions and resists numerous different stresses. The corner post is the end member of the side truss or grider which is the main load carrying member and at the same time constitutes the side retaining wall. The corner post is one of the numerous side stakes which resist the lateral thrust of the lading against the side retaining wall, which thrust is augmented by the shifting of the lading. When the end gate is in an upright position its opposite ends bear against the opposite corner post so that these posts constitute the stakes for the end retaining wall and, furthermore, the post resists the longitudinal thrusts due to the shifting of the lading. They also provide a place for the latches which hold the door in an upright position.

The corner post must be strong enough to perform its functions and yet occupy the minimum amount of space so as not to interfere with the lading and to allow the greatest amount of clearance.

An object of the invention is to provide a corner post having great strength to resist the various stresses imposed upon it and at the same time provide sufficient clearance so as not to interfere with the lading.

Another object of the invention is to obtain a corner post of minimum weight consistent with the required strength.

Fabricated or built-up corner posts are expensive and heavy and castings are impractical on account of replacements and repairs; therefore, I prefer to make the corner post from a flat metallic (preferably steel) plate and form it into the required shape by pressing it in dies, preferably after heating it.

Another object of the invention is to form a corner post from a flat steel plate.

In the drawings:

Figure 1 shows an end elevation of a railway car with my device applied thereon. In the left hand half the door is shown in a closed position while in the right hand half the door is shown in an open position, the door having been opened inwardly.

Figure 2 shows the fragmentary side elevation of Figure 1.

Figure 3 is a sectional view of line 3—3 of Figure 1.

Figure 4 is a side elevation of the corner post in detail.

Figure 5 is an end elevation of corner post in detail.

Figure 6 is a section on line 6—6 of Figure 5.

The side wall 1 of the car comprises the top chord 2 and the side sill 3. The floor 4, and sill 5, striking casting 6, carry iron 7 and end sill angle 8 are all the usual parts of the car.

The corner post comprises a side portion 10 at the side of the car and an end portion 11 at the end of the car which portions are substantially perpendicular to each other.

The side portion 10 is attached to the top side chord 2 at 12 and to the side sill 3 at 13 and is wider at the bottom than at the top to better resist the shifting tendency of the load longitudinally of the car. The side portion is provided with a vertically extending corrugation 14 which terminates within the ends of the post. This corrugation strengthens the post against the lateral forces in the car and is terminated within the post to provide room for the attachments to the side chord (12) and side sill (13) respectively.

The end portion 11 of the corner post is preferably secured to the top side chord 2 and is also secured to the end sill at 15. The upper part of this end portion is constant in width (16) for the major portion to its length and is then curved (17) to form a wider lower part 18 for connection to the end sill or underframe of the car. By maintaining a constant width, the clearance for the lading is materially increased. The outer rim of the upper part and also preferably the rim of the curved part, is formed with an outwardly projecting flange 19. This flange materially increases the strength of the corner post on a horizontal section that is in planes parallel to line 3—3 in Fig-

ure 1. Furthermore, this flange increases the bearing area or friction surface in contact with the lading. If a straight edge were used it would soon be buckled and damaged and perhaps torn or split by contact with the lading. This flange increases the strength of the end portion of the post at its outer edge and enables it to better resist the stresses due to the shifting lading.

10 When such lading as fabricated griders, pipe, telegraph poles, etc., extend beyond the corner post they frequently come in contact with it, thereby causing it to act as a post and also such lading sometimes move longitudinally of the car and if the post was not flanged (flange 19) the rim of the steel plate might damage the lading or vice-versa, the lading might damage the post.

20 The wall 20 of the corrugation 14 in the side portion is flush with the end portion 11 of this post as shown in Figure 6.

What I claim is:

1. In combination with the other elements of a railway drop end gondola car; a corner post formed of plate steel comprising a side portion and an end portion substantially perpendicular to each other, said end portion being of constant width at its upper part with its outer rim curved to form a wider lower part for connection to the underframe of the car.

2. In combination with the other elements of a railway drop end gondola car; a corner post formed of plate steel comprising a side portion and an end portion substantially perpendicular to each other, said end portion being of constant width at its upper part with its outer rim curved to form a wider lower part for connection to the underframe of the car, the outer rim of the upper part formed with an outwardly projecting flange.

3. In combination with the other elements of a railway drop end gondola car; a corner post formed of plate steel comprising a side portion and an end portion substantially perpendicular to each other, said end portion being of constant width at its upper part with its outer rim curved to form a wider lower part for connection to the underframe of the car, the outer rim of the upper part and the curved part formed with an outwardly projecting flange.

4. In combination with the other elements of a railway drop end gondola car; a corner post formed of plate steel comprising a side portion and an end portion substantially perpendicular to each other, said side portion provided with a vertical corrugation, said end portion being of constant width at its upper part with its outer rim curved to form a wider lower part for connection to the underframe of the car.

5. In combination with the other elements of a railway drop end gondola car; a corner

post formed of plate steel comprising a side portion and an end portion substantially perpendicular to each other, said side portion provided with a vertical corrugation, said end portion being of constant width at its upper part with its outer rim curved to form a wider lower part for connection to the underframe of the car, the outer edge of the upper part formed with an outwardly projecting flange.

6. In combination with the other elements of a railway drop end gondola car; a corner post formed of plate steel comprising a side portion and an end portion substantially perpendicular to each other, said side portion provided with a vertical corrugation, said end portion being of constant width at its upper part with its outer rim curved to form a wider lower part for connection to the underframe of the car, the outer rim of the upper part and the curved part formed with an outwardly projecting flange.

7. In combination with the other elements of a railway drop end gondola car; a corner post formed of plate steel comprising a side portion and an end portion substantially perpendicular to each other, said side portion provided with a vertical corrugation which terminates within said post; said end portion being of constant width at its upper part with its outer rim curved to form a wider lower part for connection to the underframe of the car.

8. In combination with the other elements of a railway drop end gondola car; a corner post formed of plate steel comprising a side portion and an end portion substantially perpendicular to each other, said side portion provided with a vertical corrugation which terminates within said post; said end portion being of constant width at its upper part with its outer rim curved to form a wider lower part for connection to the underframe of the car, the outer rim of the upper part formed with an outwardly projecting flange.

9. In combination with the other elements of a railway drop end gondola car; a corner post formed of plate steel comprising a side portion and an end portion substantially perpendicular to each other, said side portion provided with a vertical corrugation which terminates within said post; said end portion being of constant width at its upper part with its outer rim curved to form a wider lower part for connection to the underframe of the car, the outer rim of the upper part and the curved part formed with an outwardly projecting flange.

10. In combination with the other elements of a railway drop end gondola car; a corner post formed of plate steel comprising a side portion and an end portion substantially perpendicular to each other, said side portion being wider at the bottom than

at the top and secured to the top side chord and side sill of the car respectively and provided with a vertical corrugation which terminates within said post; said end portion being of constant width at its upper part with its outer rim curved to form a wider lower part for connection to the underframe of the car.

11. In combination with the other elements of a railway drop end gondola car; a corner post formed of plate steel comprising a side portion and an end portion substantially perpendicular to each other said side portion being wider at the bottom than at the top and secured to the top side chord and side sill of the car respectively and provided with a vertical corrugation which terminates within said post; said end portion being of constant width at its upper part with its outer rim curved to form a wider lower part for connection to the underframe of the car, the outer rim of the upper part formed with an outwardly projecting flange.

12. In combination with the other elements of a railway drop end gondola car; a corner post formed of plate steel comprising a side portion and an end portion substantially perpendicular to each other, said side portion being wider at the bottom than at the top and secured to the top side chord and side sill of the car respectively and provided with a vertical corrugation which ter-

minates within said post; said end portion being of constant width at its upper part with its outer rim curved to form a wider lower part for connection to the underframe of the car, the outer rim of the upper part and the curved part formed with an outwardly projecting flange.

13. In combination with the other elements of a railway drop end gondola car; a corner post formed of plate steel comprising a side portion and an end portion substantially perpendicular to each other, said end portion being of constant width at its upper part with its outer rim curved to form a wider lower part for connection to the underframe of the car, the outer rim of the upper part and the curved part formed with an outwardly projecting flange.

14. In combination with the other elements of a railway drop end gondola car; a corner post formed of plate steel comprising a side portion and an end portion substantially perpendicular to each other, said side portion provided with a vertical corrugation, the side wall of the corrugation being in the same plane as said end portion, said end portion being of constant width at its upper part with its outer rim curved to form a wider lower part for connection to the underframe of the car.

AUGUST G. SANDMAN.
